2,044,071

OSCILLATOR-DETECTOR CIRCUITS

Paul O. Farnham, Boonton, N. J., assignor, by
mesne assignments, to Radio Corporation of
America, New York, N. Y., a corporation of
Delaware

Application May 18, 1933, Serial No. 671,769

4 Claims. (Cl. 250—20)

This invention relates to oscillator-detector circuits such as may be used in receivers in which a locally generated oscillation is combined with a received carrier wave, and particularly to circuits in which a single tube functions both as the oscillator and the detector, i. e., as a modulated oscillator.

Single tube circuits have been previously proposed but have not satisfied some or all of those requirements which are desirable, if not absolutely essential, in combination oscillator-detector circuits. One requirement is that the oscillator will continue to function as the translation gain is adjusted over wide limits by varying a direct current bias, and a second requirement is that negligible voltage be transferred or induced from the oscillator into the carrier frequency circuit, i. e. the input circuit of the device.

An object of the invention is to provide an oscillator-detector circuit, including a single tube of simple design, which will satisfy both the stated requirements for circuits of this type. Another object is to provide oscillator-detector systems including a single tube having a minimum number of elements for effecting a desirable transmission control without subjecting the radio input circuit to the oscillator voltage. More particularly, an object is to provide an oscillator-detector including a tube with three grids, a cathode and plate; the plate and cathode being including in the oscillator circuit, one grid being associated with the oscillator and another grid with the input circuit, and these grids being electrostatically shielded from each other by an intervening grid.

These and other objects and advantages of the invention will be apparent from the following drawing, in which:

Fig. 1 is a fragmentary circuit diagram of a superheterodyne receiver embodying the invention, and

Figs. 2 and 3 are curve sheets comparing the characteristics of a conventional amplifier tube of the suppressor grid type with a tube particularly adapted for use in the novel circuit.

In the drawing which illustrates the detailed circuit arrangement of only the oscillator-first detector stage of a superheterodyne receiver, the reference numeral 1 identifies a carrier wave amplifier of any appropriate design which passes amplified carrier wave to the input circuit of the combined function tube 2 which is of the general type of known suppressor grid tubes in that it includes three grids G₁, G₂, G₃ between

the cathode K and the plate P. The tube 2 may be a variable-mu pentode, for example of the type known commercially as "type 58". I have found the variable-mu characteristic to be highly desirable in connection with my invention (see Proc. I. R. E., vol. 18, page 2,102, Ballantine and Snow, "Reduction of Cross-Talk in Radio Receivers by Means of Variable-Mu Tetrodes"), and in particular, a special type of variable-mu characteristic, in which appreciable current flows in the output circuit, not only at relatively high values of control-grid bias, but also at substantially zero values of control-grid transconductance.

The radio input circuit is connected between grid G₁ and the cathode and includes inductance 3, and, preferably, a tuning condenser 4.

The low potential terminal of the inductance is grounded upon the cathode for radio frequencies by the condenser 5 and is returned to the cathode, for direct current, through an adjustable source of bias potential, as indicated diagrammatically by the voltage divider 6 shunted across the bias battery 7. The intermediate grid G₂ is maintained at the radio frequency potential of the cathode K by the by-pass condenser 8, and is subjected to a direct current potential E_{c2} by a direct current connection 9 to an appropriate source of current, which is indicated diagrammatically by the battery 10.

The oscillator system includes the grid coil 11 which is tuned by condenser 12, the high potential terminal of coil 11 being connected to grid G₃ and the low potential terminal is connected by a direct current path including resistance 13 to a direct current source and through the usual series condenser 15 to ground, the condenser 15 being provided to align the oscillator carrier circuits for simultaneous tuning. The connection from resistance 13 to a direct current source, indicated by battery 16, is preferably through an adjustable device, such as voltage divider 17, which permits adjustment of the voltage E_{c3} on grid G₃. The plate coil 18 is coupled to grid coil 11, and connected between ground and the plate P through a condenser 19 which may be, and preferably is, adjustable for tuning the plate output inductance 20 to the intermediate frequency of the receiver. The output coil 20 is grounded for radio and intermediate frequencies by condenser 21 and, as indicated, the plate current supply may be completed through coil 20 by a connection 22 to the direct current source 10.

The output coil 20 may be coupled to the intermediate frequency amplifier in any appropri-

55

ate or desired manner. As illustrated, transformer coupling may be employed, the tuned circuit 23 passing the intermediate frequency voltage E to the succeeding section of the receiver, indicated generically at 24.

The design of the oscillator is preferably such that a constant frequency difference, equal to the intermediate frequency to which the output circuit 20 is tuned, is maintained between the 10 resonant frequencies of the oscillator and radio input circuit when the tuning condensers are simultaneously adjusted. The tuning element or elements 25 of the carrier wave amplifier will usually be mechanically connected to the other 15 tuning elements to permit use of the usual single control tuning system.

Reverting to the requirements to be satisfied in an oscillator-detector system, it is apparent that the control grid G_1 of the radio input circuit is shielded from the oscillator voltage by the grid G_2 which is maintained at the same alternating current potential as the cathode. The circuit described does, however, present a problem in the maintaining of oscillator action when 25 the translation gain is substantially reduced by the application of a heavy negative bias E_{c1} on the grid G_1 .

The plate or anode is common to the oscillator and intermediate frequency circuits and therefore the direct current component of the plate current decreases as the bias voltage E_{c1} is made more negative. I have found that a variable-mu tube in which a relatively high direct plate-current flow persists at low values of control-grid 30 to plate transconductance, is particularly well suited for sustained oscillation at high negative bias voltages.

The curves of Fig. 2 are plotted between negative values of the direct current control grid bias E_{c1} and the direct current plate current i_p .

Curve A represents the characteristic of one type of tube having a variable-mu control grid, which is applicable to my invention in cases 45 where a limited range of translation-gain control is tolerable, the control being obtained by varying the control-grid bias. Curve B shows the characteristic of a variable-mu tube adapted for a wider range of translation-gain control. The transconductance at any bias voltage is defined as the slope of the graph at that bias. It 50 will be noted that the tube for which curve B was plotted has higher values of plate current, for the same transconductance, than does the tube of curve A.

The significance of the control-grid plate-current curves of Fig. 2 may be seen by reference to Fig. 3, in which is plotted the amplitude of the oscillating current maintained in the plate circuit, between grid G_3 and the plate, as a function 60 of the control grid bias E_{c1} . It is apparent that the intermediate frequency output voltage E from the device, and hence the translation gain, is proportional to the slope of curves A' and B' of Fig. 65. With the type of tube for which curve A' (corresponding to curve A of Fig. 2) is plotted, the plate current becomes substantially zero at a moderate value of negative bias on the control grid, and in this region the plate-circuit oscillation stops.

The point of cessation of the plate oscillation thus imposes a limit on the extent to which the translation gain (slope of curve A') may be reduced by varying this bias. With the type of 75 tube for which curve B' (corresponding to curve

B of Fig. 2) is plotted, an appreciable current still flows to the plate for relatively large values of control-grid bias, out to the region where the slope of curve B' is substantially zero. Consequently this curve represents a condition which is 5 adapted for an extended range of translation-gain control by means of the control grid bias. It is an experimental fact that with any tube of the variable-mu type, a favorable operating condition may be realized for that particular type 10 of tube either between, or at one of, the states illustrated in Fig. 3, by adjusting the polarizing voltages on other electrodes, as for example the voltage E_{c3} .

The efficiency of the system as a frequency converter compares favorably with that of the usual separate oscillator and first detector circuits. In operation, a transrectification conductance factor of between 300 and 400 micromhos has been obtained. This factor is defined as the ratio 20 of the anode intermediate frequency current, with no anode load, to carrier voltage E_1 on the grid G_1 , and is a measure of the merit of the device as a converter of carrier-frequency oscillations to intermediate frequency oscillations. 25

I claim:

1. A combined vacuum tube oscillator and detector comprising a cathode, a plate and two control grids located at different distances from said cathode, an input circuit connected to said cathode and one control grid, said one control grid being constructed to provide a variable mu characteristic, means for resonating said input circuit to the incoming signal frequency, means for feeding back energy from the plate circuit to said second control grid, means for adjusting the frequency of the said energy feedback to a frequency differing from the applied signal frequency by an amount equal to the desired intermediate beat frequency, a screen grid interposed between said control grids and a single means for applying a positive potential to said screen grid and a greater positive potential to said plate. 30 35

2. The arrangement of the preceding claim in combination with a condenser having one side directly connected to said screen grid and its other side to said cathode. 45

3. In a modulated oscillator system, the combination of a vacuum tube having a cathode and at least four cold electrodes including a signal control grid located adjacent said cathode, of an oscillating circuit network connected between the cathode and two of the cold electrodes furthest removed from the cathode, an output circuit connected between the cathode and one of the said two cold electrodes, a tunable input circuit connected between the cathode and signal control grid, a path having negligible impedance to radio frequency currents connecting the remaining cold electrode and cathode, means for applying a steady negative bias potential to said signal control grid and means for applying steady bias potentials to the remaining cold electrodes, said signal control grid being constructed 50 to provide a variable mu characteristic of such form as to reduce to substantially zero the transconductance between said signal control grid and the farthest cold electrode. 55 60 65

4. In a modulated oscillator system, the combination of a vacuum tube having a cathode, a plate, a signal control grid, an oscillator grid, a circuit tunable to an incoming signal frequency connected between said signal control grid and cathode, means for feeding back energy from the 70 75

plate to said oscillator grid, means for adjusting the frequency of said energy feedback to a frequency differing from the incoming signal frequency by an amount equal to the desired intermediate beat frequency, a screen grid interposed between said signal and oscillator grids and means for applying steady positive voltages to said screen grid and plate, said signal control

grid being so designed with reference to said last named means that a direct current of substantial value flows between said plate and cathode when said signal control grid is made so negative with reference to said cathode as to reduce to substantially zero the value of the signal control grid-plate transconductance. 5

PAUL O. FARNHAM.
